WEATHER STRIP

Arthur H. Kuhlmann, University City, Mo.

Application November 14, 1938, Serial No. 240,242

2 Claims. (Cl. 20—69)

This invention relates to weather strips. It is an object of the invention to provide an improved weather seal for windows of metal or wood construction.

The weather strip provided by this invention will compensate for side or cross movement of the sash brought about by swelling, shrinking, or warping, so that the weather seal will not be broken and so that the sash will not stick or bind.

In addition this weather strip permits extremely easy removal of the sash without distorting or injuring the weather strip or sash in any manner.

The sash of a window equipped with this weather strip may be removed in considerably less time and with considerably less work than is necessary for other types of weather strip of the same effectiveness.

Additional objects and advantages will appear from the following detailed description of one embodiment of my invention and the accompanying drawings.

Fig. 1 is a horizontal sectional view through a portion of a window frame and upper and lower sashes to which the weather strip has been applied.

Fig. 2 is a perspective view of a section of window frame and sash with the weather strip protruding therefrom to more clearly illustrate its design.

Fig. 3 is an exploded perspective of a section of the weather strip.

Fig. 4 is a perspective view of a section of weather strip of my invention provided with a wood fillet for use as shown in Fig. 5.

Fig. 5 is a horizontal section through a portion of a window frame and upper and lower sashes equipped with my weather strip used with a wood fillet.

Fig. 6 is a perspective view of an optional form of my weather strip.

Fig. 7 is a horizontal section through a portion of a window frame and upper and lower sashes equipped with the weather strip shown in Fig. 6.

Fig. 8 is a perspective of pad useful as an air seal with this weather strip.

Referring now to the drawings, 5 and 6 are upper and lower sashes respectively. These sashes slide vertically in their respective guideways formed by the jamb 7, the inside stop 9, and the outside stop 11. A groove or channel 13 in the jamb 7 forms a seat for a spacing member or parting bead 15 which replaces the conventional parting bead of wood running from head to

sill frame members. The member 15 may be formed of some non-rusting metal such as copper, brass, zinc, or aluminum shaped as shown as a hollow U-shaped metal member provided with folded portions 17 and secured to the window as by screws 18. These folded portions form a narrow slot or guideway 19. It would, of course, be possible to provide a parting strip of equal effectiveness by securing folded metal portions to a narrow wood strip or providing guideways in any other suitable manner which would allow movement between a sealing or floating member and the guideway.

A floating member 20 formed of metal is positioned in the guideways 19 to form an air seal therewith and yet allow lateral movement thereof. I prefer to form narrow folds for guideways so that the floating member will fit snugly enough to form the air seal and yet not so snugly as to prevent lateral movement. This floating member is provided with a portion 21 to cooperate with a guideway or groove 23 on the sash as shown.

The guideway on the sash is designed to slidably engage the portion 21 of the sealing member and at the same time, to allow movement of the sash in a direction at right angles to the face of the sash. Thus the floating member and sash guideway slidably engage for longitudinal movement and at the same time, allow transverse movement of the sash. Since the floating member itself is movable laterally (in a direction parallel to the face of the sash) with respect to the sash while the sash is movable transversely (in a direction at right angles to the face of the sash) with respect to the floating member, movement of sash or frame, because of swelling, shrinking, or warping, in any direction, can be compensated. Thus any type of warpage combined with shrinkage and swelling will not impair the weather seal or cause sticking or binding of the sash. The slot or groove 23 may be metal lined if desired.

A felt pad 25 (Fig. 8) secured as by rivets 26 to a metal plate 27 is fastened to one of the sashes as shown (Fig. 5) to prevent air leakage at that point. The felt pad 25 is attached to the window sash by nailing plate 27 to the top of lower sash 6 and serves to fill the space between the parting bead 15 and the sashes 5 and 6 and thus prevent air from passing along the parting bead where the sashes overlap.

In Figs. 6 and 7, the floating member is slightly changed and provided with a fold 30 to cooperate with a guideway or track 32 which is secured to

the window as shown. These members are designed so that they will slidably engage and at the same time, allow movement of the sash in a direction substantially at right angles to its face without destroying the weather seal. A form of weather strip such as these figures illustrate may sometimes be advantageous although I prefer the form previously described, since it saves four pieces of strip per complete window and at the same time, avoids metal to metal sliding contact when the windows are raised or lowered.

In Figs. 4 and 5, a fillet 34 positioned in the groove 13 is provided to support member 15. Such a fillet may be desirable in certain installations as for instance, where channels 36 (see Fig. 5) are cut from the sash to provide a space for spring balances. In such an installation, the fillet makes it possible, without changing the design of the parting member 15 to position the slot 23 at a sufficient distance from the channels 36 to prevent the section of wood 38 from being too fragile. It can be seen, therefore, that the use of such a fillet makes it possible to use one or two standard sizes of parting members for a multitude of different frame and sash requirements.

To install my weather strip in an old window, it is only necessary to remove the old parting bead, cut the proper grooves 23 in the sash or guideways or install the suitable track or guideway 32, 30 install the parting member 15 with or without the fillet as the case may be, replace the sash, and replace the front stops. Thereafter, to remove the sash, it is only necessary to remove the front stop 9, the lower sash 6, the parting member with its associated floating members, and the upper sash 5. Such a procedure is greatly facilitated by the absence of interlocking grooves, springs, and nailed strips so common with many of the present types of weather strip. It can be seen from the drawings that this weather strip will allow much greater shrinkage without impairing the air seal than the present types. Thus in an average size strip, a shrinkage of one inch may be compensated for. In actual installations, I prefer to allow a clearance of approximately $\frac{1}{8}$ inch between each side of the sash and the stile 7 in order to insure an easy running window. This additional clearance allows the window to swell without causing binding or sticking.

It can also be seen that a warpage is provided for in the relative movement between the guideways 23 and the portions 21 of the floating members. Since provision has been made for movement in two directions which are at right angles to each other, it is apparent that this weather strip will allow deformation of the sash in any direction without interfering with the sealing action of the weather strip or without causing the sashes to stick or bind.

Many of the present type of strips provide parting beads and other parts in two sections, i. e., an upper and lower section, in order that once weather strip is installed, the sash can be removed to get at weights, cords, or balances for repair work. The parting member and floating members of the weather strip of this invention are, however, full length, i. e., they extend from head to sill of the frame. This is made possible by the design of the strip which allows the sash to be easily removed. Such construction results in economy both of manufacture and installation.

Heretofore, it has been impossible to use aluminum in many types of weather strip because of

the tendency of aluminum to bind when contacting surfaces of aluminum slide against each other. In my weather strip, both the parting member 15 and the floating members 20 may be of aluminum as these members do not slidably engage each time the window is raised and lowered but merely move laterally with respect to each other for relatively short distances. This movement is not sufficient to cause binding of the aluminum. The sliding contact is between the wood slot 23 and the folded portion 21 of the sealing member. This is a metal to wood contact in the preferred form and is self-lubricating and of extremely long life. Since a metal to metal sliding contact is not necessary in the preferred embodiment, the various members may be formed of aluminum which previously was not satisfactory for such weather strips.

It will thus be obvious to those skilled in the art that my weather strip affords numerous advantages over the present types of weather strip. The ease of installation and saving of time incident to the installation thereof are especially desirable. The fact that the weather strip allows movement in any direction automatically compensates for minor mistakes in the cutting of the groove in the sash or in the installing of the strip. The manufacturer of pre-fabricated windows equipped with such a weather strip is especially aided by the simplicity and ease of installation of this weather strip.

While the above description and the accompanying drawings illustrate preferred embodiments of my device, I do not wish to limit it to the specific construction and arrangement of parts shown, as various modifications, substitutions, additions, and omissions may be made without departing from the spirit and scope of my invention as defined by the appended claims.

40 I claim:

1. A weather strip comprising a grooved guideway, a floating member, and a wooden sash, said guideway being formed of aluminum and having a main portion and a substantially U-shaped second portion, said guideway being arranged to be positioned in a window frame and be stationary with respect to the said window frame, said floating member being formed of aluminum and comprising an L shaped member having a plane section that engages the substantially U-shaped second portion of the guideway, a bend, and folded end, a longitudinal groove in the wooden sash to receive the folded end of the floating member, the said second portion of the guideway being dimensioned to receive the plane end of the floating member thereby forming an air seal therebetween, and to permit lateral movement between the said second portion and the plane end of the floating member, the longitudinal groove in the wooden sash and said folded end of the floating member being dimensioned to form an air seal therebetween and to permit ready longitudinal movement of the sash relative to the floating member, said floating member having a frictional rather than a positive engagement with the elements of the weather seal.

2. A weather strip comprising a grooved guideway, a floating member, and a wooden sash, 70 said guideway being formed of metal and having a main portion and a substantially U-shaped second portion, said guideway being arranged to be positioned in a window frame and be stationary with respect to the said window frame, said floating member being formed of metal and com-

prising an L shaped member having a plane section that engages the substantially U-shaped second portion of the guideway, a bend, and a folded end, a longitudinal groove in the wooden member, the said second portion of the floating member being dimensioned to receive the plane end of the floating member thereby forming an air seal therebetween and to permit lateral movement between the said second portion and the plane end of the floating member positioned in the said

5 second portion, the longitudinal groove in the wooden sash and said folded end of the floating member being dimensioned to form an air seal therebetween and being arranged to provide metal to wood bearing contact and thereby permit ready longitudinal movement of the sash relative to the floating member, said floating member having a frictional rather than a positive engagement with the elements of the weather seal.

ARTHUR H. KUHLMANN.
